No. 738,249.

PATENTED SEPT. 8, 1903.

I. SNOW.

SHUTTLE DETECTING MEANS FOR LOOMS.

APPLICATION FILED JUNE 22, 1903.

NO MODEL.

UNITED STATES PATENT OFFICE.

ISAAC SNOW, OF LAWRENCE, MASSACHUSETTS, ASSIGNOR TO DRAPER COMPANY, OF HOPE DALE, MASSACHUSETTS, A CORPORATION OF MAINE.

SHUTTLE-DETECTING MEANS FOR LOOMS.

SPECIFICATION forming part of Letters Patent No. 738,249, dated September 8, 1903.

Application filed June 22, 1903. Serial No. 162,474. (No model.)

To all whom it may concern:

Be it known that I, ISAAC SNOW, a citizen of the United States, and a resident of Lawrence, county of Essex, State of Massachusetts, have

5 invented an Improvement in Shuttle-Detecting Means for Looms, of which the following description, in connection with the accompanying drawings, is a specification, like characters on the drawings representing like parts.

10 This invention relates to means for detecting improper boxing of the shuttle in a loom, it being well known that in certain types of looms it is highly important for the shuttle to occupy a definite position in the shuttle-box when some other mechanism is to coöperate therewith.

In looms of the Northrop type—for instance, such as shown in United States Patent No. 529,940—mechanism is provided to 20 automatically furnish the running shuttle with a fresh supply of filling when necessary without interrupting the operation of the loom. If the shuttle is not properly positioned to receive the fresh filling-supply, the 25 various parts of the apparatus are strained or broken, and for this reason a shuttle-feeler or detector has been provided to determine whether or not the shuttle is properly boxed for filling replenishment when it is called for.

30 If the shuttle is in proper position, the replenishing mechanism operates; but if the shuttle is not in proper position it is detected by the feeler, and the operation of the replenishing mechanism is prevented, thus avoiding a 35 smash or injury to the apparatus. The ordinary shuttle-feeler has a tendency in some cases when the point of the shuttle projects somewhat across the feeler-path to slip off the point, due either to springing of the feeler away

40 from the shuttle or because of some looseness in the bearing on which the feeler rocks. As a result the feeler fails to prevent filling replenishing notwithstanding the fact that the shuttle is improperly positioned, although, 45 so far as can be detected by the eye, the various parts are properly set or adjusted to effect the desired result.

My present invention has for its object the production of simple and effective means for

overcoming the objections referred to and to 50 surely prevent filling replenishment if the shuttle-feeler engages the shuttle, no matter how slight such engagement may be.

The various novel features of my invention will be described hereinafter, and particularly pointed out in the following claims.

Figure 1 is a top or plan view of the right-hand end of a loom-*lay*, its shuttle-box, and the shuttle-feeler in normal position embodying one form of my invention. Fig. 2 is 60 a similar view, but showing the *lay* as nearly forward and the feeler as having begun its feeling movement, the shuttle being shown as far enough out of the box to engage the feeler. Fig. 3 is an enlarged right-hand side 65 elevation of the end of the feeler and its tip. Fig. 4 is a longitudinal section thereof on the line 4 4, Fig. 3; and Fig. 5 is a perspective view of the tip-holder and the tip separated from each other.

The *lay* A³, automatically self-threading shuttle S, adapted to receive a filling-carrier b, the upturned arm Y, fulcrumed on the stud a on a bracket A¹⁰, secured on the loom side A^X and having a finger n', the pin 30 on arm Y, 75 and the arm d¹², fast on the controlling or operating rock-shaft d', may be and are all substantially as in United States Patent No. 683,423. A spring S^X (see dotted lines, Figs. 1 and 2) is fixedly held at one end and at its 80 other end is attached to the arm d¹², holding the latter down against pin 30 and normally maintaining the arm Y and its attached parts in retracted inoperative position, the filling-replenishing mechanism, which may be of the 85 type illustrated in said patent, being governed as to its operation by the rock-shaft d', as therein provided for. Turning of the rock-shaft in the direction of arrow 50 upon filling failure or upon substantial exhaustion 90 of the filling in the shuttle effects the operation of the replenishing mechanism in well-known manner. The arm Y in said patent is bent rearwardly at its upper end to constitute a shuttle-feeler y, and when filling replenishment is called for the lifting of the arm d¹² permits the arm Y and the shuttle-feeler y to 95 rock rearwardly on stud a as a fulcrum to ex-

tend across the lay in front of the mouth of the shuttle-box. If the shuttle is properly boxed, replenishment is effected; but if the feeler engages the projecting end of the shuttle at the box-mouth (indicating that the shuttle is not properly positioned) the operation of the replenishing mechanism is prevented by or through the finger n' and the devices (not herein shown) with which it cooperates.

To prevent the failure of the feeler to properly act, as hereinbefore referred to, when the shuttle is improperly positioned, I have provided the feeler with a movable tip so constructed that if it engages with the shuttle even to a very slight extent it will turn in such manner that the area of contact between the tip and the shuttle will be very materially increased. This acts to retain the feeler in proper engagement with the shuttle to prevent filling replenishment and completely obviates any tendency of the feeler to spring laterally or slide away from the shuttle, and thereby permit replenishment. It will be understood that at such time the feeler as a whole will yield slightly as the lay beats up, swinging on its fulcrum a .

Referring to Figs. 3 and 4, the rearwardly-extended feeler y has an elongated slot y' to receive a bolt 5 , passed through a tip-holder y^3 , a nut 6 securely clamping the latter to the feeler. The tip-holder (shown separately in Fig. 5) consists of a flat plate having an overhanging flange y^3 on its upper edge to fit into a cut-away part 10 , Fig. 3, of the upper edge of the feeler y , the flange preventing the tip-holder from turning on the bolt. Parallel ears y^4 project laterally from the plate, the end of the flange near the upper ear being concaved, as at y^5 , concentric with holes 12 in the ears in alignment with each other, the ears being set in from the upper and lower edges of the plate, as is shown in Figs. 3 and 5.

The feeler-tip, as herein shown, is preferably made as a casting and comprises a body portion t , having a longitudinally-convex outer face t' and parallel substantially circular ears t^2 , extended from the opposite face of the body at one end and at right angles thereto. The ears have central aligned holes t^3 , Fig. 5, and are far enough apart to easily receive between them the ears y^4 of the tip-holder, a pivot-pin 20 , extended through the holes in the two sets of ears, pivotally connecting the tip with the tip-holder, the upper ear t^2 fitting into the concaved end y^5 of the flange. A spring s^x is coiled around the pin between the ears of the tip, one end of the spring resting against the tip-holder between its ears, while its other end is positioned in a notch 22 in the flat face t' of the tip between the ears, as shown in Fig. 3. The spring is so wound that normally the tip is held in the position shown in Figs. 1 and 2 and full-line position, Fig. 4, the upright inner corner of the face t' engaging the end of the tip-holder. Now when the feeler y is swung rearwardly

on the fulcrum a when the filling is to be replenished the tip-holder and tip will move across the lay in front of the mouth of the adjacent shuttle-box B^x as the lay beats up, provided the shuttle is properly boxed, and filling replenishing will then be effected. Should the shuttle be improperly positioned, however, so that its point extends beyond the mouth of the box and into the path of the tip, as shown in Fig. 2 and in dotted lines, Fig. 4, the completion of the forward movement of the lay will cause the tip to engage the shuttle and the tip will be turned on its fulcrum 20 into dotted-line position, Fig. 4. It will be seen that this turning of the tip will present a greater area of contact between its convex face t' and the shuttle, so that the feeler cannot by any possibility be sprung or pushed sidewise to slip or slide past the shuttle-point, and the feeler as a whole will be retracted or yield and prevent the operation of the replenishing mechanism in well-known manner. When the tip is turned, as has been described, the flat faces 3 of the ears y^4 engage the face t' of the tip and serve as stops to limit its turning movement, so that then the tip is substantially rigid with the feeler-arm Y . So long as there is any engagement of the tip with the shuttle, no matter how slight, the tip will be turned and its contact area with the shuttle increased to operate as has been described. As the outer end of the tip is normally offset from its fulcrum 20 and at the outer side thereof or toward the shuttle-box, the yielding movement of the tip relatively to the feeler will occur when the shuttle is improperly boxed. The tip-holder can be adjusted on the feeler-arm by means of the bolt 5 and slot y' .

My invention is not restricted to the precise construction and arrangement shown and described, as the same may be modified or rearranged in various particulars without departing from the spirit and scope of the invention.

Having fully described my invention, what I claim as new, and desire to secure by Letters Patent, is—

1. In a loom, the lay provided with a shuttle-box, a shuttle, a movable shuttle-feeler to detect improper positioning of the shuttle in the shuttle-box, and a tip yieldingly mounted on the feeler, to engage the shuttle when the latter is improperly positioned.

2. In a loom, the lay provided with a shuttle-box, a shuttle, a shuttle-feeler movable across the lay in front of the mouth of the shuttle-box when the shuttle is properly positioned therein, and a laterally and yieldingly movable tip mounted on the feeler, to engage the shuttle when the latter is improperly positioned.

3. In a loom, the lay provided with a shuttle-box, a shuttle, a movable shuttle-feeler to detect improper positioning of the shuttle in the shuttle-box, a tip movable with and also relatively to the feeler, to engage the shuttle when

improperly positioned, and means to limit such relative movement of the tip when so engaged.

4. In a loom, the lay provided with a shuttle-box, a shuttle, a movable shuttle-feeler to detect improper positioning of the shuttle in the shuttle-box, and a spring-controlled tip mounted on the feeler and movable by engagement with the shuttle to increase the area of contact between it and the tip and insure the detecting action of the feeler when the shuttle is improperly positioned.

5. In a loom, the lay provided with a shuttle-box, a shuttle, a movable shuttle-feeler to detect improper positioning of the shuttle in the shuttle-box, and a tip yieldingly mounted on the feeler and having a convex face to engage the shuttle when the latter is improperly positioned in the shuttle-box.

20 6. In a loom, the lay provided with a shuttle-box, a shuttle, a shuttle-feeler movable across the lay in front of the mouth of the shuttle-box when the shuttle is properly positioned therein, a shuttle-engaging tip yieldingly mounted on the feeler, and means to adjust the tip thereon.

7. In a loom, the lay provided with a shuttle-box, a shuttle, a shuttle-feeler movable across the lay in front of the mouth of the shuttle-box when the shuttle is properly positioned therein, a shuttle-engaging tip having a convex contact-face and pivotally mounted on the feeler to move laterally relatively thereto, a spring to retain the tip in normal position,

and means to limit its pivotal movement relatively to the feeler. 35

8. In a loom, the lay provided with a shuttle-box, a shuttle, a shuttle-feeler movable across the lay in front of the mouth of the shuttle-box when the shuttle is properly positioned 40 therein, a shuttle-engaging tip pivotally mounted on the feeler and having its free end laterally offset from its fulcrum, and a controlling-spring for the tip.

9. In a loom, the lay provided with a shuttle-box, a shuttle, a movable shuttle-feeler to detect improper positioning of the shuttle in the shuttle-box, and a relatively movable tip on the feeler, to engage the shuttle when the latter is improperly positioned in the shuttle- 50 box.

10. In a loom, the lay provided with a shuttle-box, a shuttle, a movable shuttle-feeler to detect improper positioning of the shuttle in the shuttle-box, and a relatively movable tip 55 on the feeler having its extremity offset from the path of movement of the feeler toward the shuttle-box, to engage and be moved by the shuttle relatively to the feeler when the shuttle is improperly positioned in the shuttle- 60 box.

In testimony whereof I have signed my name to this specification in the presence of two subscribing witnesses.

ISAAC SNOW.
